UNITED STATES PATENT OFFICE.

GEORGE HENRY GARNET, OF ALLENTOWN, PENNSYLVANIA.

FLOOR-OILER.

SPECIFICATION forming part of Letters Patent No. 769,376, dated September 6, 1904.

Application filed January 5, 1904. Serial No. 187,857. (No model.)

To all whom it may concern:

Be it known that I, GEORGE HENRY GARNET, a citizen of the United States, residing at Allentown, in the county of Lehigh and State of Pennsylvania, have invented certain new and useful Improvements in Floor-Oilers; and I do hereby declare the following to be a full, clear, and exact description of the invention, such as will enable others skilled in the art to which it appertains to make and use the same.

This invention relates to devices for applying oil or other liquids to floors; and it consists in the novel construction and combination of the parts hereinafter fully described and claimed.

In the drawings, Figure 1 is a longitudinal section through the floor-oiler. Fig. 2 is a cross-section through the floor-oiler, taken on the line *xx* in Fig. 1. Fig. 3 is a sectional plan view taken on the line *yy* in Fig. 1 and drawn to a smaller scale.

A is a large reservoir for the oil or other liquid which is to be applied to the floor.

B is a stopper for closing the opening through which the said reservoir is filled. This stopper is arranged at the top of the reservoir, and it is provided with any suitable valve or slide *b* for the admission of air; but this air-valve may be arranged at any other point at the upper part of the reservoir instead of being mounted on the stopper.

C is a flat plate below the reservoir *A*, and *D* is an oil-chamber between the said plate and reservoir. The plate *C* has flanges or extensions *c*, which project outwardly beyond the oil-chamber *D*, and *E* represents screw-threaded studs which project upwardly from the said flanges at suitable intervals around the said oil-chamber.

F is an oiling pad or sheet of felt secured below the plate *C*. The oiling-pad is preferably formed of a piece of pile-fabric carpet; but other similar absorbent fabric, such as cloth or felt, may be used. The edges of the oiling-pad are bent around the flanges *c* and are provided with holes, which are slipped over the studs *E*, and *e* represents thumb-nuts which clamp the edges of the oiling-plate in position.

c The plate *c* has large openings *c'* in it, and

G represents tubular guide-boxes secured to the said plate around its said openings. These guide-boxes are filled with absorbent material *g*—lamp-cotton or lamp-wick—and portions of the wick hang over the top edges of the said guide-boxes into the oil in the oil-chamber. The absorbent material or lamp-wick absorbs the oil contained in the oil-chamber and conducts it to the oiling-pad *F*. The main reservoir *A* has a discharge-nozzle *h*, which projects from its bottom part within the oil-chamber *D* and extends within the said chamber to close to the plate *C*. This nozzle is arranged under the middle part of the reservoir and between the tubular guides *G*.

The floor-oiler is provided with an operating-handle *H* for pushing it about, and this handle is secured to it at any convenient point and is arranged at any desired angle.

The reservoir and the oil-chamber are first filled with oil and the stopper and the air-valve are closed. The floor is oiled by pushing the device about in contact with its surface, and the edges *i* of the oiling-pad form buffers, which prevent injury to furniture when the oiler is pushed against it. As the oil is applied to the floor and the supply of oil in the oil-chamber becomes exhausted the air-valve is opened more or less and from time to time, so as to supply the said oil-chamber with more oil.

What I claim is—

1. In a floor-oiler, the combination, with an oil-chamber having a flat base-plate and tubular guide-boxes projecting upward from the said plate, of a reservoir for supplying the said chamber with liquid, absorbent material in the said boxes, and a pad of textile material secured under the said base-plate in contact with the said absorbent material.

2. In a floor-oiler, the combination, with an oil-chamber having a flat base-plate and tubular guide-boxes projecting upward from the said plate, of a reservoir having an outlet-nozzle which depends within the said chamber, an air-valve at the upper part of the said reservoir, absorbent material in the said boxes, and a plate of textile material secured under the said base-pad in contact with the said absorbent material.

3. In a floor-oiler, the combination, with an oil-chamber having a flat base-plate provided with openings and projecting flanges, of a pad of textile material arranged over the said 5 openings with its edges overlapping the said flanges, and means for clamping the said edges to the said flanges.

In testimony whereof I have affixed my signature in the presence of two witnesses.

GEORGE HENRY GARNET.
